ELECTRIC DISCHARGE TUBE

Johannes Gijsbertus Wilhelm Mulder, Eindhoven, Netherlands, assignor, by mesne assignments, to North American Philips Company, Inc., New York, N. Y., a corporation of Delaware

Application December 22, 1954, Serial No. 476,959

Claims priority, application Netherlands January 6, 1954

5 Claims. (Cl. 313—170)

The invention relates to an electric discharge tube comprising a liquid cathode and a preferably annular auxiliary anode.

In discharge tubes comprising a liquid cathode and an auxiliary anode it is often difficult to obtain favourable conditions for burning the auxiliary arc with the vapor pressures varying owing to the variable load for all load values. An arc burning under unfavourable conditions may readily extinguish in the case of external disturbances and moreover, the auxiliary arc may oscillate, which may give rise to spontaneous ignition without the required control signal being applied to the control-grid or, other electrode. The invention has for its object to obviate these disadvantages.

According to the invention, in an electric discharge tube comprising a liquid cathode and an auxiliary anode, the latter is arranged relatively to the liquid cathode and to any means provided therein for fixing the cathode spot in a manner such that the shortest space between different points of the lower side of the auxiliary anode and the liquid cathode or the means provided therein for fixing the cathode spot varies widely, i. e. in a ratio of at least 1:5, preferably at least 1:10.

By the construction described above it is ensured that both with high and low vapour pressures a favourable discharge path for the auxiliary discharge is obtained between the auxiliary anode and the cathode. For known reasons it is desired that the auxiliary discharge should apply to the lower side of the auxiliary anode. Thus the auxiliary discharge may burn quietly both with low and high vapour pressures in a small distance and a long distance.

The invention will now be described more fully with reference to the accompanying drawing, which shows an electric discharge tube according to the invention.

The wall of the electric discharge tube is constituted for the major part by the glass body designated by 1, in which the current through-connection of the anode 3 is sealed with the aid of a cap 2. Around the anode inlet insulator 4 is clamped a screening sleeve 5, which supports the control-grid 6. The screening sleeve 5 terminates over two interconnected coaxial screens 7 and 8, which are supported from a ceramic plate 9. The apertures 10 and 11 of the screens 7 and 8 respectively are covered by a central plate 12 in order to counteract mercury sputtering from the cathode and the effect of any violent evaporation.

2

The ceramic plate 9 supports an auxiliary anode 13, having a terminal 14. The cathode mercury 15 contains a molybdenum anchor 16, which is conductively connected to the bottom of the cathode vessel 17. The wall portions 17 and 1 are sealed to one another in a vacuum-tight manner. The cathode furthermore contains an ignition electrode 18 of semi-conductive material. The terminal of electrode 18 is not shown. The smallest space between the annular auxiliary anode 13 and the anchor 16 is 2 mms. and the largest space is nearly 20 mms.

What is claimed is:

1. An electric discharge device comprising a liquid cathode; a main anode; and a cylindrical auxiliary anode located between said cathode and said main anode and having an edge proximal to said cathode arranged so that one portion of said edge is closer to said cathode than another portion of said edge whereby an auxiliary arc between said cathode and said auxiliary anode will burn quietly at high and low vapor pressures in said electric discharge device.

2. An electric discharge device comprising a liquid cathode; a main anode; and a hollow cylindrical auxiliary anode located between said cathode and said main anode so that electrons from said cathode pass through said auxiliary anode on the way to said main anode, said auxiliary anode having a lower edge proximal to said cathode arranged so that one portion of said edge is much closer to said cathode than another portion of said edge whereby an auxiliary arc between said cathode and said auxiliary anode may burn quietly at both high and low vapor pressures in said electric discharge device.

3. An electric discharge device comprising a liquid cathode; a conductive metal vessel holding said liquid; an anchor in the form of a closed retaining wall attached to the bottom of said vessel and extending above the level of said liquid; a main anode; and a hollow cylindrical auxiliary anode located between said cathode and said main anode and having a lower edge proximal to said anchor arranged so that a portion of said edge is closer to said anchor than another portion of said edge, said anchor serving to fix the portion of said liquid from which electron discharge takes place and said auxiliary anode cooperating with said anchor to provide an auxiliary arc which will burn quietly at both high and low vapor pressures in said electric discharge device.

4. The electric discharge device of claim 3 in which said auxiliary anode and said anchor are coaxially aligned.

5. An electric discharge tube comprising a liquid cathode; a main anode; and a hollow cylindrical auxiliary anode located between said cathode and said anode, said auxiliary anode having an edge facing said cathode whose distance from the cathode varies from maximum to minimum in a ratio of about 1:10.
